UNITED STATES PATENT OFFICE.

MANSFIELD M. WEST, OF CLEVELAND, OHIO, ASSIGNOR TO THE UNIVERSAL SHOE PLATE COMPANY, OF CLEVELAND, OHIO, A CORPORATION OF OHIO.

DESIGN FOR A SHOE-PLATE.

59,394.

Specification for Design.

Patented Oct. 11, 1921.

Application filed October 3, 1918. Serial No. 256,753. Term of patent 14 years.

To all whom it may concern:

Be it known that I, MANSFIELD M. WEST, a citizen of the United States, residing at Cleveland, in the county of Cuyahoga and State of Ohio, have invented a new, original, and ornamental Design for Shoe-Plates, of which the following is a specification, reference being had to the accompanying drawing, forming part hereof, wherein—

Figure 1 is a perspective view; Fig. 2, a

plan view; Fig. 3, an end elevation; and Fig. 4, a side elevation of a shoe plate, exhibiting my new design.

I claim:—

The ornamental design for a shoe plate, as shown.

MANSFIELD M. WEST.
